DESIGN FOR A VEGETABLE GRATER

Harry Schechtel, Los Angeles, Calif.

Application April 22, 1946, Serial No. 128,860

Term of patent 14 years

(Cl. D89—1)

To all whom it may concern:

Be it known that I, Harry Schechtel, a citizen of the United States of America, residing at Los Angeles, in the county of Los Angeles and State of California, have invented a new, original, and ornamental Design for a Vegetable Grater, of which the following is a specification, reference being had to the accompanying drawing, forming part thereof.

The drawing is a perspective view of a vegetable grater, showing my new design.

The opposite side and opposite end of the grater are similar to the side and end illustrated except for the elimination of the crank.

I claim:

The ornamental design for a vegetable grater, as shown and described.

HARRY SCHECHTEL.
